UNITED STATES PATENT OFFICE.

ARMAND GODEFRÖID, OF BERLIN, GERMANY.

COIN-ASSORTING APPARATUS.

Application filed January 14, 1924. Serial No. 686,193.

To all whom it may concern:

Be it known that I, ARMAND GODEFRÖID, a citizen of Germany, residing in Berlin W. 30, Hohenstaufenstrasse 50, Germany, have 5 invented new and useful Improvements in and Relating to Coin-Assorting Apparatus, of which the following is a specification.

My invention relates to improvements in cash registers, and more particularly to the 10 coin assorting apparatus therefor comprising a counting board adapted to receive the coins paid by the customer and to be tilted for dropping the coins on a travelling tape divided into compartments and moving below 15 a transparent plate permitting for a certain length of time the inspection of the coins by the cashier and the customer, said tape delivering the coins to an assorting apparatus adapted to convey the coins into 20 compartments of the drawer of the cash register.

The object of the improvements is to provide an assorting apparatus of this type, by means of which a faultless distribution of 25 the coins to the individual compartments of the drawer is insured, and which is not subject to obstruction by the coins. With this object in view my invention consists in providing a plurality of assorting chutes or 30 gutters having their inlet ends located in position for receiving the coins from the tape, so that when tilting the counting board for dropping the coins on the tape each gutter or chute receives one or at the most two 35 coins. Therefore in each gutter only one coin passes at a time along the assorting openings provided in the wall of the gutter and it is not possible that a small coin is prevented from dropping through the proper 40 discharge opening by a larger coin obstructing the said opening. In the practical construction of the apparatus I prefer to direct the assorting gutters from the chutes to opposite sides, the gutters connected to the 45 right hand chutes leading to the left hand side of the cash register, and vice versa. However, in this construction it is impossible directly to convey the coins discharged 50 from the different chutes into the proper compartments of the drawer, because similar coins are discharged at opposite sides of the cash register. Therefore another feature of my invention consists in providing means for conveying the coins discharged from the as-

sorting gutters to the correct compartments 55 of the drawer. In order that my invention be more clearly understood several examples embodying the same have been shown in the accompanying drawings, in which the same reference characters have been used in all 60 the views to indicate corresponding parts. In said drawings—

Fig. 1^a—1^b, is a plan view of a coin assorting apparatus of a cash register, in which the member for conveying the coins to the 65 compartments of the gutter is in the form of a horizontal stationary disk divided into annular guide ways and cooperating with a rotary coin sweeper for conveying the coins to the proper compartments of the drawer, 70

Fig. 2, is an elevation partly in section on the line 2—2 of Fig. 1^a—1^b, the chutes of the assorting gutters being shown in a diagrammatical way,

Fig. 3, is an elevation looking from the 75 right in Fig. 2 and showing the said chutes in a diagrammatical way,

Fig. 4, is a detail view showing one of the chutes,

Fig. 5, is a longitudinal section on the line 80 5—5 of Fig. 4,

Fig. 6 is a plan view showing a modification of the coin conveying member, the coins being conveyed to the individual compartments of the drawer by means of a rotary 85 disk divided into annular guide ways,

Fig. 7, is a cross section taken on the line 7—7 of Fig. 6,

Fig. 8, is a detail view showing one of the gates of the conveying member and the gate 90 operating mechanism,

Fig. 9, is a plan view showing another modification of the conveying member, the coins being conveyed to the individual compartments of the drawer by means of a rotary disk divided into sector-like compartments,

Fig. 10, is an elevation partly in section taken on the line 10—10 of Fig. 9, and

Figs. 11 to 13, are detail views showing 100 different parts of the mechanism shown in Figs. 9 and 10.

In the example shown in Figs. 1^a to 5 the assorting mechanism comprises a counting board 1 the breadth of which taken in the 105 direction from the customer to the cashier is such that just a coin of the largest diameter can be placed thereon. The length

of the counting board is such that a suitable number of coins of like or different diameters can be placed thereon one behind the other.

5 The counting board 1 is formed with two trunnions 2 mounted in the side walls 3 of the cash register, so that the counting board can be rocked about its front edge disposed at the side of the cashier. At the discharge 10 side of the counting board there is an endless conveying tape 4 divided by transverse bars 5 into transverse compartments of equal area and adapted to be moved with its top part in the direction towards the 15 cashier. The said compartments are adapted to receive the coins discharged from the counting board when rocking the same, and it is adapted to be operated by the cashier depressing the crank 6 for 20 operating the rocking mechanism for the counting board. Any suitable means may be provided for operating the tape. As shown the mechanism consists of an arm 8 keyed to the shaft 6' of the crank 6 and carrying a 25 pawl 9 cooperating with a ratchet wheel 10 secured to one of the shafts carrying the tape. The mechanism for rocking the counting board 1 consists of an arm 7' secured to the crank shaft and connected with 30 the counting board by a link 7. The tape 4 is disposed below a glass plate 11 extending to a line away from the rear end of the tape, so that only the uppermost transverse compartment of the tape is uncovered to 35 permit the discharge of the coins from the counting board 1 to the tape. By the mechanism 8, 9, 10 intermittent movement is imparted to the tape, and the coins discharged into the compartments can be inspected by the customer as well as by the 40 cashier so that any disagreement as to the amount paid by the customer can be settled before the coins are distributed. When a compartment containing coins arrives in the 45 lowermost or front position, and the tape is further moved one step the coins drop into chutes 12, each chute receiving only one or at the most two coins. In the construction shown in the figures four chutes 12 are provided. Each of the chutes is connected with 50 an assorting gutter 13 providing a beveled guide way and having its side walls slightly inclined to one side in transverse direction, as is shown in Figs. 2 and 3. The chutes 55 12 are disposed one beside the other and in close relation one to the other and they extend each over one fourth of the breadth of the tape, so that each chute can take up at a time only one or at the most two coins located on the tape. By reason of the small 60 number of coins to be distributed at a time by each chute, the apparatus can not be obstructed, and it is impossible, that several coins move through the apparatus one 65 beside the other so as to prevent the dis-

charge of a coin through the proper assorting opening.

To reduce the breadth of the cash register as far as possible I prefer to dispose the assorting gutters so as to cross each other in 70 the manner shown in Fig. 2, the gutters 13 connected to the chutes 12 located at the right of the apparatus leading to the left hand side of the cash register and vice versa. The position of the gutters 13 will 75 be clearly understood from Fig. 2, while Fig. 3 illustrates the same in a diagrammatical way.

At its bottom end each of the assorting gutters 13 is formed with a series of elongated assorting openings 14 the height of which taken from the bottom of the gutter is successively increased according to the diameters of the individual coins to be assorted, so that from the coin rolling downwardly within the gutter at first the smallest one, thereafter the median ones and finally the largest ones are assorted by dropping through the openings 14. At their outer ends the gutters 13 are open in order that a 90 coin rolling by accident along the corresponding opening 14 is discharged from the gutter and into a receptacle for non-assorted coins. This part of the construction is important because otherwise the coins passing 95 the openings 14 would obstruct the lower part of the gutter. Each of the openings 14 discharges into a chute 15 having the construction shown in Figs. 4 and 5, Figs. 2 and 3 showing the said chutes only in a diagrammatical way.

By providing crossing assorting gutters 13 like coins are discharged at the right hand side and at the left hand side of the cash register, the coins of larger diameters 105 being discharged at points which are a considerable distance away from each other. Therefore means must be provided to convey the coins discharged from the individual assorting gutters to the proper compartments of the drawer, so that the similar coins are all discharged into the same compartment of the gutter.

In the construction shown in Fig. 3 the said conveying apparatus consists of a stationary disk 16 disposed in the frame 17 of the cash register and divided by circular partition walls 18 into annular compartments of different breadths corresponding to the diameters of the coins. The chutes 15 120 of the individual gutters 13 are disposed so that the discharges of the chutes of equal sizes are disposed on circles exactly above the corresponding annular compartments of the disk 16. Therefore like coins 125 discharged from one or the other of the gutters 13 all get into the same annular compartment of the disk 16. For conveying the coins contained within the said annular compartments to the corresponding compart- 130

ments of the drawer 19 disposed immediately below the disk 16 the said coins are advanced on the bottom of the compartments, until they get to openings 20 made in the 5 bottom of the disk and immediately above the corresponding compartments of the drawer 19. As shown in Figs. 1^a to 3 between the discharges of the chutes 15 and the conveying disk 16 a sweeping apparatus 10 is provided which as shown in Figs. 1^a to 3 consists of a rotary member 21 disposed above the disk 16 and rotatably mounted by means of an anti-friction bearing 22 or the like above the conveying disk 16, 18, which 15 member is provided at both sides with sweepers 23 in the form of brushes or arms one for each compartment and projecting to the bottom of the compartments and adapted upon rotation of the member 21 to shift 20 the coins discharged from the chutes 15 into the compartments to the openings 20 and into the corresponding compartments of the drawer 19. The sweeper 21 is operated by opening and closing the drawer. As shown 25 the drawer has a rack 24 secured to one of its side walls and engaging in a spur gear 25 keyed to a vertical shaft 26 and adapted to transmit rotary movement imparted thereto by the drawer through pulleys 27 and 30 29 and a rope 28 to the vertical axis 30 of the arm 21. The length of the rack 24 is such that the rotation of the member 21, 23 is automatically interrupted as soon as the rear wall of the drawer 19 passes the opening 35 20 when retracting the same from the cash register. When closing the drawer the sweeping member is operated in the opposite direction without acting on any coins.

In Figs. 6-8 I have shown a modification 40 in which the conveying apparatus consists of a disk 31 divided into annular compartments and rotatably mounted by means of its axis 32 and adapted to be rotated from the drawer 19 through the intermediary of 45 mechanism similar to the one described with reference to Figs. 1 to 3 and likewise indicated by the reference characters 25-29. The bottoms of the annular compartments are provided each with a number of openings 33 disposed radially to each other, as 50 is shown in Fig. 6. The openings 33 are normally closed by gates 34 provided at the bottom side on the disk and rockingly mounted at 34'. Each of the gates is formed 55 with an upwardly projecting arm 35, and it is normally held in closing position by means of a weight 36 or a spring. Above the disk 31 and at right angles to the direction of the movement of the drawer 19 a bar 37 60 is secured to the side walls of the apparatus, and to the bottom side of the said bar brushes or arms 38 two for each of the compartments are secured, which brushes are so disposed on the bar 37 that they pass into 65 the annular compartments of the disk 31 directly above the corresponding compartments of the drawer 19. When rotating the disk 31 the coins contained within the annular compartments are successively brought into engagement with the brushes 38 and held back thereby, until one of the openings 33 passes below the same. Now the arm 35 of the corresponding gate 34 engages the bar 37, and it is rocked thereby in a direction opposite to the direction of the rotation of the disk 31, so that it is opened and the coin drops through the opening into the correct compartment of the drawer 19. In this construction of the conveying apparatus the disk 31 rotates always in the same direction indicated in Fig. 6 by the arrow 39, and the operating mechanism 24, 25, 26, 27, 28, 29 is provided at any suitable point with a clutch permitting transmission of the movement of the drawer 19 only when closing the same, it being inoperative when opening the same.

In the modification shown in Figs. 9-13 the conveying apparatus for distributing the coins to the compartments of the drawer 14 70 comprises a rotary frame 41 divided by radial partition walls 42 into compartments in the form of sectors. The bottom of each of the said compartments consists of a gate in the form of a sector 43 rockingly mounted 75 on a radial axis 44. The axis 44 projects beyond the outer circumference of the frame and the projecting ends 44' are different in length and they are cranked downwardly, the downwardly bent arms 46 being likewise 80 different in length. The arms 46 carry weights 47 tending to hold the gates 43 in horizontal positions for closing the sector-shaped compartments of the frame.

In this modification the drawer is not 85 divided into longitudinal compartments, but into a number of compartments disposed one beside the other and one behind the other as is shown in Fig. 9, the dimensions of the compartments being such that they can receive all the coins confined in one compartment of the disk.

In order to discharge the compartments of the frame into the proper compartments of the drawer 40 the compartments of the 90 drawer are provided with stop members 48 of different lengths, and each of the said stop members is adapted for cooperation with the crank arm 46 of one of the shafts 44, which cooperation is possible only when 95 the said compartment of the drawer is exactly in position below the corresponding compartment of the frame 41. By the stop member 48 the crank arm 46 is rocked so as to set the gate 43 in vertical or inclined position for permitting the discharge of the coins into the compartment of the drawer.

In the example shown in the figures the frame 41 is operated by means of gearing comprising a rack 49 secured to one side of 100

the drawer, two spur gears 51 and 52 keyed to a shaft 50, a circular rack secured to the circumferential wall 45 of the frame, and a clutch (not shown) permitting the transmission of power in one direction only.

In constructions of the type shown in Figs. 9 to 13, in which the coins are supplied to the compartments of the drawer by means of a frame having compartments in the form of sectors, the coins must be retained within the chutes 15, until the proper compartment of the frame 41 is in position below the corresponding chute. For this purpose the chutes 15 are normally closed at their bottom ends by gates 54 formed with downwardly directed arms 55 and normally closed by means of springs 56. From the partitions 42 there rise arms 57, and the radial distance of the said arms from the center of the frame 31 is different in all the partitions. The said arms 57 are disposed so that the circles described thereby upon rotation of the frame are exactly below the chutes containing the coins corresponding to the arms. If now one of the arms 57 engages the arm 55 of the gate 54 of the chute 15 corresponding thereto, the lever 55 is rocked against the tension of the spring 56, and the gate 54 is opened, so that the coins confined within the chute drop into the corresponding compartment of the frame 41 disposed below the same. The same operation is repeated with the other chutes, which therefore discharge the coins each into the corresponding compartment of the frame. If now upon rotation of the frame 41 the downwardly directed end 46 of the axis 44 corresponding to the said compartment engages the corresponding arm 48 of the drawer 40, the crank arm 46 is rocked and the bottom 43 is turned about its axis, so that the coins confined within the corresponding compartment drop into the compartment of the drawer 40 designed for collecting the said coins. But the other arms 48 are inoperative with reference to the said crank arm 46, so that above the other compartments of the drawer 40 the bottom 43 is not rocked and the coins confined in the compartments are not discharged into the drawer.

It will be understood that instead of the conveying apparatus described above chutes may be provided for conveying the coins discharged from the gutters 13 to the proper compartments of the drawer 19. However such chutes must be inclined at comparatively large angles, because the coins discharged from the assorting opening 14 drop on the said chutes in flat positions, so that they do not roll on the said chutes, and sliding of the coins requires a strong inclination of the chutes. Therefore in such constructions the height of the assorting gutters 65 above the drawer and that of the cash reg-

ister is large. Therefore I prefer the conveying apparatus comprising a horizontal disk or frame.

While in describing the invention reference has been made to particular examples embodying the same I wish it to be understood that my invention is not limited to the constructions shown in the drawings, and that various changes may be made in the general arrangement of the apparatus and the construction of its parts without departing from the invention.

I claim:

1. In a coin assorting apparatus, a plurality of aligned hoppers, a coin chute connected to each hopper, the coin chutes from a plurality of said hoppers extending in one direction and diverging from each other, the coin chutes of another plurality of said hoppers extending in the opposite direction and diverging from each other, each coin chute being provided with means to assort the different coins supplied thereto.

2. In a coin assorting apparatus, the combination, with a plurality of coin assorting devices each adapted to assort different coins supplied thereto, said assorting devices being so disposed as to cross each other, of means common to all of said assorting devices for supplying coins thereto.

3. In a coin assorting apparatus, the combination, with a plurality of coin assorting devices each adapted to assort different coins supplied thereto, said assorting devices being so disposed as to cross each other, of means common to all of said assorting devices for supplying coins thereto, and means to collect like coins discharged from said assorting devices.

4. In a coin assorting apparatus, the combination, with a coin conveying apparatus divided into compartments adapted to convey a plurality of coins, of a plurality of assorting devices in position for receiving each a part of the coins conveyed by said compartments.

5. In a coin assorting apparatus, the combination, with a coin conveying apparatus divided into compartments, adapted to convey a plurality of coins, of a plurality of assorting devices in position for receiving each a part of the coins conveyed by said compartments, and means to collect like coins discharged from said assorting devices.

6. In a coin assorting apparatus, the combination, with a coin conveying apparatus divided into compartments adapted to convey a plurality of coins, of a plurality of assorting gutters in position for receiving each a part of the coins conveyed by said compartments, said gutters being disposed so as to extend respectively from one side of the conveying apparatus to the opposite one.

7. In a coin assorting apparatus, the combination, with a plurality of coin assorting

- devices each adapted to assort different coins supplied thereto, of means common to all of said assorting devices for supplying coins thereto, a coin conveying disk having annular compartments each in position for collecting like coins from said devices, and means to collect the coins deposited in said compartments. 5
8. In a coin assorting apparatus, the combination, with a plurality of coin assorting devices, each adapted to assort different coins supplied thereto, of means common to all of said assorting devices for supplying coins thereto, a stationary conveying disk having annular compartments each in position for collecting like coins from said devices, and a rotary sweeping member adapted to collect the coins deposited in said compartments. 10
9. In a coin assorting apparatus, the combination, with a plurality of coin assorting devices each adapted to assort different coins supplied thereto, of means common to all of said assorting devices for supplying coins thereto, a drawer having compartments for different coins, a coin conveying disk having annular compartments, each in position for collecting like coins from said devices, and means to convey the coins deposited in the compartments of the disk into corresponding compartments of the drawer. 15
10. In a coin assorting apparatus, the combination, with a plurality of coin assorting devices each adapted to assort different coins supplied thereto, of means common to all of said assorting devices for supplying coins thereto, a drawer having compartments for different coins, a coin conveying disk having annular compartments each in position for collecting like coins from said devices and conveying the same into said compartments of the drawer, and means operated by the movement of said drawer to convey the coins deposited in the compartments of the disk into corresponding compartments of the drawer. 20
11. In a coin assorting apparatus, the combination with a plurality of coin assorting devices each adapted to assort different coins supplied thereto, of means common to all of said assorting devices for supplying coins thereto, a coin receiving member having annular compartments each in position for collecting like coins from said devices, each compartment having a bottom discharge, a 50 sweeping member adapted upon rotation of one of said members to shift the coins contained within said compartments to said discharges, and means for rotating one of said members. 55
12. In a coin assorting apparatus, the combination with a plurality of coin assorting devices each adapted to assort different coins supplied thereto, and containers for collecting the coins assorted by the devices, of means common to all of said assorting devices for supplying coins thereto, a member divided into a number of compartments positioned to receive coins from said containers, each compartment having a bottom discharge, means for causing the coins deposited in said compartments to be discharged from the bottom of the compartments, and separate chambers to receive the coins discharged from said compartments. 60
13. A coin assorting apparatus including a coin display device having a positively moved element for shifting the coins within view of the operator, aligned hoppers arranged to receive coins from said element, 65 diverging chutes arranged to receive the coins from the hoppers, one chute being associated with each hopper, each chute having openings to discharge coins of different sizes, and a set of spouts associated with the openings of each chute for discharging assorted coins from the chutes. 70
- In testimony whereof I hereunto affix my signature in the presence of the witness.
- ARMAND GODEFROID.
- Witness:
- EMIL KOTTERITSCH.
